US0D1082834S

(12) **United States Design Patent** (10) Patent No.: **US D1,082,834 S**
(45) Date of Patent: ** Jul. 8, 2025

(54) **DISPLAY SCREEN WITH A GRAPHICAL USER INTERFACE**

(71) Applicant: **Meta Platforms, Inc.**, Menlo Park, CA (US)

(72) Inventors: **Frederick Scott Gottesman**, Kentfield, CA (US); **Patrick Francis Keenan**, Toronto (CA); **Aaron Albonetti**, Long Beach, CA (US); **Wade Campbell**, Seattle, WA (US); **William Siemers**, Seattle, WA (US); **Annabel Strauss**, New York City, NY (US); **Ishwarya Venkatachalam**, Atlanta, GA (US); **Kevin Victor Wong**, Renton, WA (US)

(73) Assignee: **Meta Platforms, Inc.**, Menlo Park, CA (US)

(**) Term: **15 Years**

(21) Appl. No.: **29/851,843**

(22) Filed: **Aug. 31, 2022**

(51) LOC (15) Cl. **14-04**

(52) U.S. Cl.

USPC **D14/485**

(58) **Field of Classification Search**

USPC D14/486, 487-495
See application file for complete search history.

(57) **CLAIM**

The ornamental design for a display screen with a graphical user interface, as shown and described.

DESCRIPTION

The FIGURE is a front view of a display screen with a graphical user interface showing the claimed design. The broken lines shown in this FIGURE illustrate an electronic device and portions of a display screen with a graphical user interface that form no part of the claimed design.

1 Claim, 1 Drawing Sheet
